Patented May 23, 1922.

UNITED STATES PATENT OFFICE.

JOHN KIBLER, JR., OF WALLA WALLA, WASHINGTON, ASSIGNEE OF ONE-HALF TO
HARRY E. DE WITT, OF WALLA WALLA, WASHINGTON.

FOLDING CAMP BED.

1,417,253.

Specification of Letters Patent. Patented May 23, 1922.

Application filed August 18, 1920. Serial No. 404,355.

To all whom it may concern:

Be it known that I, JOHN KIBLER, Jr., a citizen of the United States, residing at Walla Walla, in the county of Walla Walla 5 and State of Washington, have invented certain new and useful Improvements in Folding Camp Beds, of which the following is a specification.

This invention relates to folding camp beds adaptable for tourists and has for its 10 object to provide a bed which may be folded in a small space; a further object is to provide a bed in which the act of sitting up renders its flexible bottom yieldingly rigid.

15 A further object is to provide a bed which is cheap to construct and which may be rolled or folded into a small space.

With these and other objects in view reference is now had to the accompanying 20 drawings in which—

Fig. 1 is a perspective view of the bed set up;

Fig. 2 shows the ball and socket joint with part in section;

25 Fig. 3 is a fragment and shows the independent tightening means;

Fig. 4 is a rear view of a leg;

Fig. 5 is a side elevation of Fig. 3, showing a leg;

30 Fig. 6 shows a major part folded on itself with bottom removed;

Fig. 7 is a side elevation of the independent tightening means; and

Fig. 8 is a fragment showing position of 35 frame when taking down or setting up.

Having reference to the drawings, like numerals refer to like parts throughout and the numeral 1 refers to the frame which consists of two major parts *a* and *b* respectively;

40 each of which consists of an end piece 2 having bent ends forming the female portion 3 of a hinge, while the side rail 4 terminates, at the hinge end, in a flattened portion to complete the hinge. The bent ends provide

45 the required allowance of space for snug folding purposes and permits the bottom 5 to extend laterally the full width of the rails as shown in Fig. 1.

The side rails are joined together centrally 50 of the frame in a novel manner, the respective ends thereof being formed into a ball and socket joint, one end forming the ball 6 while the corresponding end forms the socket 7, the purpose of which will be presently explained. Over the rail is a sliding sleeve 8

which when brought over the ball and socket joint maintains rigidity at this point.

The ball and socket joint being an important feature, I will now proceed to explain its function.

60 Referring to Fig. 8 it will be noted that the sleeve 8 has been moved to expose the joint and that the side rail is broken at this point. Any tension now existing on the end piece 2 draws it in as shown by the solid lines 65 therein; this relieves the tension on the frame and the opposite joint is then easily broken. Now, to set up the bed, (after unfolding) one of the side rails is made rigid, and the free ends of the other side rail are 70 now brought together, the ball and socket now unite and form a flexible union which may be manipulated to take up the tension 75 without danger of slipping, after which the sleeve 8 is brought over the joint and completes the process. Thus is the importance of the ball and socket joint at this point shown, as without this the completing of this set up of the frame would be an awkward matter requiring a hinge with its attendant danger of pinching the operator 80 during manipulation.

The frame is provided with legs 9 which support the free end of the frame, the opposite end being supported by the running 85 board 10 of a car to which the end of the frame is fastened by means of U bolts represented as at 11. By this means a certain amount of flexibility in a vertical plane is established wherewith to aid in folding up 90 the bed, after which the U bolts, together with any convenient fastening means for the roll formed by folding, will prevent the bed from falling from the running board.

The bottom 5 of the bed consists of a 95 yielding material, such as canvas, and is adjustable as to tension by the lacing 12 as shown in Fig. 1. It is obvious that other means of adjustment may be employed, such as straps, with equal effectiveness.

100 Another principal feature of my invention is the independent adjustable tightening means which consists of a cable or chain 13 which is passed along the edge of the bottom, with one of its ends permanently attached to one end rail and with its other end attached adjustably to the other end rail through the medium of an adjusting means consisting of the usual hooked bolt and thumbnut 14. By this means as great ten- 110

sion as desired may be placed on the edge of the bottom without an undue tension being put on the bottom. Other cables or chains may be distributed beneath the bottom if desired.

Having thus described my invention, I claim—

1. In a folding camp bed, a frame consisting of two major parts, each of said parts 10 foldable upon itself, and each of said parts terminating in one part of a ball and socket joint, to register with the corresponding socket and ball of its fellow, a sliding sleeve covering said joint to maintain rigidity 15 thereat, legs foldably attached to said frame, an independently adjustable yielding bottom attached to said frame, adjustable tightening members supporting said bottom, coop-

eratingly and an adjusting means attached to said frame.

2. In a folding camp bed, a self stretching and folding frame, consisting of two major parts, each of said parts foldable upon itself, and each of said parts terminating in one part of a ball and socket joint, to register 25 with the socket and ball of its fellow, a sliding sleeve covering said joint, to maintain rigidity thereat, legs foldably attached to said frame, an adjustable yielding bottom attached to said frame, independently adjustable tightening members supporting 30 said bottom, and a means for tightening said members operably attached to said frame.

In testimony whereof I affix my signature.

JOHN KIBLER, JR.
